RAILWAY BRAKING APPARATUS

Robert M. Gilson, Pittsburgh, Pa., assignor to The Union Switch & Signal Company, Swissvale, Pa., a corporation of Pennsylvania

Application February 28, 1948, Serial No. 11,975

13 Claims. (Cl. 303—20)

1

My invention relates to railway braking apparatus, and particularly to braking apparatus of the type comprising wheel engaging braking bars located beside a track rail and movable toward the rail into braking positions by means of a fluid pressure operated motor and moved away from the rail into non-braking positions by suitable biasing means such as gravity.

In the form of braking apparatus described and claimed in Letters Patent of the United States No. 2,372,550, granted to Harold C. Clausen and Linnie K. Hedding, on March 27, 1945, for Railway braking apparatus, an electromagnetic inlet valve controls the supply of air to a fluid pressure motor which operates the brake, and another electromagnetic valve controls the exhaust of fluid from the motor. Three Bourdon tubes are provided which respond to the pressure of the fluid in the motor. Each Bourdon tube moves a movable contact between a low pressure stationary contact which it engages when the motor pressure is below a first predetermined value, and a high pressure stationary contact which it engages when the motor pressure is above another value substantially greater than said first predetermined value. The three Bourdon tubes are set to operate their movable contacts at different ranges of motor pressure. A remote manual electrical controller is connected to the Bourdon tubes and the valves through line wires. This controller has five positions. In one extreme position, the electromagnetic exhaust valve is energized, and in the other extreme position the electromagnetic inlet valve is energized. In each of the three intermediate positions, one of the three Bourdon tubes is placed in control of the two valves. A condenser is connected in parallel with the winding of the inlet valve to delay its closure when the valve controlling circuit is opened. This delay is provided to insure that when the inlet valve controlling circuit is opened by one of the Bourdon tubes, the motor pressure will be increased somewhat above the contact opening pressure, thereby preventing chattering of the Bourdon tube contact. Since a substantial amount of energy must be stored in this condenser, a condenser of large capacity is required. The only commercially practicable type of condenser having the required large capacity is an electrolytic condenser, which has asymmetric capacity characteristics. It is therefore essential to the use of this type of condenser that it always be energized with current of the same polarity. The control circuits of the Clausen et al. patent are arranged so that the electrolytic con-

2

denser is always energized by current of the same polarity.

It is an object of my invention to provide an electrical control system of the type described, in which the number of line wires between the electrical controller and the valve winding is reduced below the minimum available on previous circuits.

Another object of my invention is to provide an improved remote electrical control system for an electrical device having asymmetric properties, including two selectively closable electrical circuits for energizing the device with current of the same polarity, both of which circuits include a line wire in which current flows in opposite directions in the two circuits.

I accomplish these objects of my invention by providing four line wires between the five-position controller and the electromagnetic valve, utilizing each line wire in at least two positions of the controller, and providing asymmetric units in the valve control circuits to block currents of one polarity and admit currents of the opposite polarity.

Other objects and characteristic features of my invention will become apparent as the description proceeds.

I shall describe one form of apparatus embodying my invention, and shall then point out the novel features thereof in claims.

The accompanying drawing is a somewhat diagrammatic illustration of one form of apparatus embodying my invention.

Referring to the drawing, the reference character 1 designates one track rail of a stretch of railway track, which track rail, as here shown, is secured to a rail support 2 mounted on an adjacent pair of the usual crossties 3, only one cross-tie being visible in the drawing. Associated with the rail 1 is a car retarder comprising two braking bars A1 and A2 located on opposite sides of rail 1. Each of these braking bars comprises, as usual, a brake beam 4 and a brake shoe 5.

The braking bars A1 and A2 are arranged to be moved toward and away from the rail 1 through the medium of a lever 6 which is pivotally mounted at one end on a pivot pin 8 carried by the rail support 2, and a lever 8 which is pivotally mounted intermediate its ends on the pivot pin 7. The lever 6 is inclined upwardly and extends away from the rail 1 and is provided in its upper surface with a groove 6a which receives the braking bar A1. The one end 8a of the lever 8 is likewise inclined upwardly and extends away from the rail 1 at the opposite side of the rail

from the lever 6, and the other end 8b of the lever 8 is inclined downwardly and extends away from the rail 1 below the lever 6. The end 8a of the lever 8 is provided in its upper surface with a groove 8c, similar to the groove 6a in the lever 6, which groove receives the braking bar A2. The parts are so arranged and so proportioned that if the outer or free ends of the levers 6 and 8 are moved apart, the braking bars will be moved toward the rails into their effective or braking positions. When the braking bars occupy their braking positions, the brake shoes will engage the opposite side faces of a car wheel traversing rail 1, and will retard the speed of the car. The center of gravity of the lever 6 and braking bar A1 is considerably to the left of the pivot pin 7 so that this lever will normally tend to rotate in a counterclockwise direction about the pivot pin. Similarly, the center of gravity of the lever 8 and braking bar A2 is to the right of the pivot pin 7 so that this lever will normally tend to rotate in a clockwise direction about the pivot pin. It will be apparent, therefore, than when no force is applied to the free ends of the levers 6 and 8 to move them apart, the free ends of these levers will move toward each other, thereby moving the braking bars to their ineffective or non-braking position in which they are illustrated in the drawing.

The levers 6 and 8 are arranged to be moved apart by means of a fluid pressure motor M comprising a cylinder 9 containing a reciprocable piston 10 which is attached to the inner end of a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 8b of the lever 8 by means of an adjustable eyebolt 14 and pivot pin 15. Fluid pressure may be admitted to the cylinder 9 between the upper end of the cylinder and the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, thereby separating the levers 6 and 8, and hence moving the braking bars toward their effective or braking positions. It will be obvious that when the braking bars are moved to their braking position, they will exert a braking force which is proportional to the pressure of the fluid supplied to the cylinder 9.

The supply of fluid pressure to the cylinder 9 of motor M is controlled by means of two fluid pressure operated poppet valves 18 and 19, which poppet valves, in turn, are controlled by means of two electromagnetic valves V1 and V2. These electromagnetic valves are similar and each comprises a valve stem 20 biased to an upper position by means of a spring 21, and provided with a winding 22 and an armature 23. When valve V1 is energized, as shown in the drawing, valve stem 20 of this valve moves downwardly against the bias exerted by the associated spring 21, and under these conditions a pipe 24 is connected with a pipe 25 which is constantly supplied with fluid pressure, usually compressed air, from a suitable source not shown in the drawing. When valve V1 is deenergized, however, pipe 24 is disconnected from pipe 25 and is connected with atmosphere through a port 26.

When valve V2 is energized, valve stem 20 of

this valve moves downwardly, and connects the pipe 25 with a pipe 27, but when valve V2 is deenergized, as shown in the drawing, pipe 27 is disconnected from the pipe 25 and is connected with atmosphere through a port 28.

The two fluid pressure operated poppet valves 18 and 19 are both located in the same valve body 29, and associated with each poppet valve is a spring 18a or 19a which constantly biases the valve to a closed position. Formed in the valve body 29 above the valve 19, and in axial alignment therewith, is a cylinder 30 containing a reciprocable piston 31 which is operatively connected with the valve 19. The upper end of cylinder 30 is connected with the previously referred to pipe 27, and it will be apparent, therefore, that when valve V2 is deenergized so that pipe 27 is connected with atmosphere, spring 19a will hold valve 19 closed and piston 31 in its upper position, but that, when valve V2 is energized, so that pipe 27 is connected with pipe 25, the fluid pressure which is then supplied to pipe 27 will force piston 31 to its lower position, thus opening valve 19. When valve 19 is opened, cylinder 9 of motor M is connected to pipe 25 through pipe 17, a pipe 32, a chamber 33 formed in valve body 29, valve 19, and a chamber 34 formed in valve body 32; but when this valve 19 is closed, cylinder 9 is disconnected from pipe 25.

The valve body 29 is also formed with a second cylinder 35 containing a reciprocable piston 36 which is operatively connected with the valve 18, and the upper side of which is subjected to the pressure in the pipe 24. When valve V1 is energized, the fluid pressure which is then supplied to pipe 24 forces piston 36 to its lower position thereby opening valve 18, and under these conditions, cylinder 9 of motor M becomes connected with atmosphere through pipes 17 and 32, chamber 33, valve 18, a chamber 37 formed in valve body 29, and a pipe 38. When valve V1 is deenergized, however, spring 18a moves valve 18 to its closed position, and piston 36 to its upper position, thus disconnecting cylinder 9 from atmosphere.

It follows from the foregoing that when valve V2 is energized, fluid pressure will be supplied to cylinder 9 from pipe 25, and that, when valve V1 is energized cylinder 9 will become connected with atmosphere.

The valves V1 and V2 are controlled in part by a plurality of pressure responsive devices P20-30, P45-55, and P70-80, each comprising a Bourdon tube, numbered, respectively, 39, 40, and 41, connected to the pipe 17, and hence subjected to the pressure of the fluid in the region of cylinder 9 between piston 10 and the upper end of the cylinder. Each Bourdon tube positions a movable contact, numbered respectively 39a, 40a, and 41a, which respectively move between low pressure stationary contacts 39b, 40b, and 41b, and high pressure stationary contacts 39c, 40c, and 41c. The pressure responsive devices P20-30, P45-55 and P70-80 are so constructed and so adjusted that they will operate successively as the pressure in the region of cylinder 9 between the piston 10 and the upper end of the cylinder increases. For example, for all pressures below 20 pounds per square inch, the movable contact of each of these devices is closed against its associated low pressure contact. If the pressure exceeds 20 pounds per square inch, however, contact 39a-39b of device P20-30 opens, and if the pressure exceeds 30 pounds per square inch, con-

75

tact 39a-39c of device P20-30 closes. In a similar manner, the pressure responsive devices P45-55 and P70-80 are adjusted to open their contacts 40a-40b and 41a-41b at 45 and 70 pounds per square inch, respectively, and to close their contacts 40a-40c and 41a-41c at 55 and 80 pounds per square inch, respectively. Of course, these specific pressures are not essential but are only mentioned for purposes of explanation.

The valves V are also controlled by means of a manually operable lever L which, as here shown, is capable of assuming five positions, indicated by dotted lines in the drawing, and designated by the reference characters p1 to p5, inclusive. The lever L controls a plurality of contacts each designated by the reference character 42 with a distinguishing suffix corresponding to the position of the lever in which the corresponding contact is closed. For example, contact 42-1 is closed in the p1 position of the lever, contact 42-2 in the p2 position of the lever, etc. Contacts 42-4a and 42-4b are both closed in the p4 position of the lever.

Lever L is usually located at a point remote from the braking apparatus, as in the control cabin of a classification yard car retarder system, and is connected with the braking apparatus by means of line wires extending from the control cabin to the braking apparatus. As shown in the drawing, lever L occupies its p1 or "off" position, which is the position which it normally occupies when no cars are to be retarded, and all of the contacts of levers L with the exception of contact 42-1 are therefore open.

Valve V2 is then deenergized, but valve V1 is energized over a circuit which may be traced from the positive terminal of battery C, through common line wire 45, the winding 22 of valve V1, wire 44, an asymmetric unit R1 in its low resistance direction, line wire 43, and contact 42-1 of lever L to the negative terminal of battery C. Since valve V2 is deenergized, pipe 27 is cut off from the supply of fluid pressure, and since valve V1 is energized, cylinder 9 is connected with atmosphere. The braking bars are therefore held in their ineffective or non-braking positions by gravity. The low pressure contact of each of the pressure responsive devices is closed and the high pressure contacts are open.

A condenser D is connected in parallel with the winding 22 of valve V2 between a positive junction 46 and a negative junction 47. The function of this condenser is to maintain the energization of the winding 22 of valve V2 for a time after its energizing circuit is opened. Since the condenser must store a substantial amount of energy if the winding energization is to be continued for an appreciable period, a condenser of large capacity is required. In one particular installation, a condenser of sixteen microfarads capacity was used in parallel with a winding of one hundred and thirty ohms resistance. The necessity for a high capacity condenser makes it desirable to use an electrolytic condenser. Since such a condenser has asymmetric capacitance properties, it is desirable that it be energized by a potential of the same polarity at all times.

Now let it be assumed that the operator wishes to make a comparatively light brake application. To do this he moves the lever L from its p1 position to its p2 position, thereby opening contact 42-1 and closing contact 42-2. The 75

opening of contact 42-1 interrupts the circuit which was previously closed for valve V1. The closing of contact 42-2 places the valves V1 and V2 under control of the pressure responsive device P20-30.

Deenergization of valve V1 disconnects pipe 24 from supply pipe 25 and connects pipe 24 with the atmosphere. The pressure in the upper end of cylinder 35 therefore decreases rapidly, and as soon as this pressure has decreased to a predetermined value, for example, 15 pounds per square inch, spring 18a closes valve 18, thus disconnecting cylinder 9 from the atmosphere.

Since the pressure in cylinder 9 is at this time less than 20 pounds per square inch, the closing of contact 42-2 completed a circuit for valve V2. This circuit may be traced from the positive terminal of battery B through contact 42-2, line wire 43, contacts 39a and 39b of pressure responsive device P20-30, wire 43, positive junction 46, winding 22 of valve V2 and condenser D in parallel, negative junction 47, an asymmetric unit R2 in its low resistance direction, and common line wire 45 to the common terminal of batteries B and C. Valve V2 therefore becomes energized and connects pipe 27 with supply pipe 25 so that fluid at full line pressure is now supplied to the upper end of cylinder 30, thus causing piston 31 to move downwardly and open valve 19. Pipe 25 thereby becomes connected with pipe 17 and cylinder 9, so that air at full line pressure is supplied to cylinder 9 to move the braking bars to their effective or braking position. As soon as the pressure in the upper end of cylinder 9 reaches 20 pounds per square inch, contact 39a of pressure responsive device P20-30 moves away from contact 39b, thereby opening the circuit just traced for valve V2. Because of the action of condenser D, winding 22 of valve V2 will remain energized for a short time after contact 39a separates from contact 39b, thereby causing the pressure in cylinder 9 to continue increasing sufficiently to move contact 39a a substantial distance away from contact 39b. As soon as energization of winding 22 of valve V2 is terminated, valve V2 returns to the position shown in the drawing, thereby venting cylinder 30 to atmosphere and allowing valve 19 to close under the influence of spring 19a. The supply of fluid under pressure to cylinder 9 is thereby cut off. If the pressure in the motor cylinder 9 now decreases below 20 pounds per square inch, then contacts 39a and 39b again close and valve V2 is again energized to supply air under pressure to the motor cylinder. If the pressure in motor cylinder 9 should now increase above 30 pounds per square inch, then contact 39a would engage contact 39c, thereby completing an energizing circuit for winding 22 of valve V1. This circuit may be traced from the positive terminal of battery B through contact 42-2, line wire 43, contacts 39a and 39c of pressure responsive device P20-30, wire 44, winding 22 of valve V1, common line wire 45 and the common terminal of batteries B and C. When valve V1 is energized, valve 18 is opened, thereby venting the motor cylinder 9 to atmosphere until such time as the pressure in the motor cylinder again decreases below 30 pounds per square inch, whereupon contacts 39a and 39c again open. When this happens, valve V1 is again deenergized, thereby closing valve 18 and preventing further escape of the fluid from motor cylinder 9. It may therefore be seen that when lever L occupies its p2 position, the braking bars will be held in their braking posi-

tions by a pressure of between 20 and 30 pounds per square inch.

The circuits so far described for the p_1 and p_2 positions of the controller L are similar to those described in the Clausen et al. Patent No. 2,372,550, previously referred to. The circuits to be described below contain the novel features of my invention.

If the operator moves lever L to its p_3 position, the valves V1 and V2 are placed under control of the pressure responsive device P45—55, which maintains the motor pressure between 45 and 55 pounds per square inch. Under these conditions, the energizing circuit for valve V2 may be traced from the positive terminal of battery B through contact 42—3, a line wire 49, an asymmetric unit R3 in its low resistance direction, contacts 40a and 40b of pressure responsive device P45—55, wire 48, positive junction 46, winding 22 of valve V2 and condenser D in parallel, negative junction 47, asymmetric unit R2 in its low resistance direction, and common wire 45 to the common terminal of batteries B and C. The corresponding energizing circuit for valve V1 may be traced along the circuit just described to contact 40a, and thence through contact 40c, wire 44, winding 22 of valve V1, and common line wire 45 to the common terminal of batteries B and C.

If the operator moves lever L to position p_4 , the valves V1 and V2 are placed under control of the Bourdon tube 41, which maintains the motor cylinder pressure between 70 and 80 pounds per square inch. Under these conditions, the energizing circuit for valve V2 may be traced from the common terminal of batteries B and C through contact 42—4b, a line wire 50, positive junction 46, winding 22 of valve V2 and condenser D in parallel, negative junction 47, a wire 51, contacts 41b and 41a operated by Bourdon tube 41, an asymmetric unit R4 in its low resistance direction, line wire 49, contact 42—4a to the negative terminal of battery C. The corresponding energizing circuit for valve V1 may be traced from the common terminal of batteries B and C along common line wire 45, winding 22 of valve V1, wire 44, contacts 41c and 41a operated by Bourdon tube 41, asymmetric unit R4 in its low resistance direction, line wire 49, and contact 42—4a to the negative terminal of battery C.

If the operator moves controller L to position p_5 , then valve V2 is energized independently of any of the Bourdon tubes. This energizing circuit for valve V2 may be traced from the positive terminal of battery B through contact 42—5, line wire 50, positive junction 46, winding 22 of valve V2 in parallel with condenser D, negative junction 47, asymmetric unit R2 in its low resistance direction, and common line wire 45 to the common terminal of batteries B and C.

It should be noted that in the positions p_3 , p_4 , and p_5 of lever L, all of the line wires are used for at least two positions. Line wire 49 is used in both positions p_3 and p_4 , and line wire 50 is used in both positions p_4 and p_5 . It should also be noted that each energizing circuit for winding 22 of valve V2 supplies the condenser D with potential of the proper polarity. The asymmetric units R2, R3, and R4 block currents of improper polarity and admit currents of proper polarity so that each of the line wires 45, 49, and 50 may be used in two circuit controlling positions of lever L. The current flows in line wire 49 in opposite directions in positions p_3 and p_4 , but the asym-

metric units are arranged so that the current flows through winding 22 of valve V2 in the same direction in both of those positions.

Although I have herein shown and described only one form of railway braking apparatus embodying my invention, it is understood that various changes and modifications may be made therein within the scope of the appended claims without departing from the spirit and scope of my invention.

Having thus described my invention, what I claim is:

1. Control apparatus, comprising an electrical winding, an electrolytic condenser connected in parallel with said winding to delay deenergization thereof, two electrical circuits for energizing said winding and said condenser from a remote point with direct electric potentials of the same polarity, including a line wire extending between said winding and said point, direct electrical energy supply means, means at said point for connecting said line wire to said supply means so that at times a current of one polarity flows in the line wire and at other times a current of opposite polarity flows in the line wire, and means connecting said line wire to said winding including oppositely poled asymmetric units so that the current in the winding is of the same polarity regardless of the polarity of the current in said one line wire.

2. Control apparatus, comprising an electrical device having asymmetric properties, two selectively closable electrical circuits for energizing the device from a remote point with direct electric potentials of the same polarity, including a line wire extending between the device and said point, direct electrical energy supply means, circuit controlling means at said point for connecting the line wire to the supply means so that when one of said circuits is completed a current flows through the line wire in one direction and when the other circuit is completed a current flows through the line wire in the opposite direction, and means connecting the line wire to the device including oppositely poled asymmetric units so that the electric potential supplied to the device is of the same polarity when either circuit is completed.

3. Control apparatus comprising an electrical device having asymmetric properties, and means including two selectively closable electrical circuits for supplying to the device direct electric potentials of the same polarity, including a line wire forming a part of both circuits and through which current flows in opposite directions in the two circuits.

4. Control apparatus as in claim 3, including two oppositely poled asymmetric units connecting said line wire to opposite terminals of said device.

5. Control apparatus comprising an electrical winding, means associated with said winding for delaying deenergization thereof when and only when said winding has previously been energized by direct current of a particular polarity, first and second selectively closable electrical circuits for energizing the winding from a remote point with electrical current of said polarity, including a line wire forming a part of both circuits and extending between the winding and said point, direct current supply means, circuit controlling means at said point for connecting the line wire to the supply means so that when one of said circuits is completed a current flows through the line wire in one direction and when the other circuit is completed a current flows through the

line wire in the opposite direction, and means connecting the line wire to the winding including oppositely poled asymmetric units so that the current flowing through the wire passes through the winding with said particular polarity regardless of its direction of flow through the wire.

6. Control apparatus as in claim 5, including a fluid pressure motor, an electromagnetic valve having a winding and effective when the winding is energized to admit fluid to the motor, first and second pressure responsive devices subject to the pressure in the motor, and first and second contacts respectively opened by said first and second pressure responsive devices at different pressures, in which said winding is connected in both said circuits, and said first and second contacts are connected in said first and second circuits, respectively, and in which said delaying means is effective to insure that the motor pressure continues to increase for a time after said contacts open.

7. Control apparatus as in claim 5, in which said first circuit includes a connection between the line wire and one terminal of the winding, a second line wire, and a first one of said asymmetric units poled to pass current of said particular polarity; and in which said second circuit includes a connection between said first-mentioned line wire and the opposite terminal of the winding, a third line wire, and another of said asymmetric units poled to pass current of said particular polarity.

8. Railway braking apparatus comprising a braking bar located in the trackway beside a track rail, and control apparatus for said bar as in claim 6, in which said fluid pressure motor is connected to said bar for moving it toward the track rail into a braking position in which it will engage a part of a car to retard the speed of the car.

9. Control apparatus, comprising an electrical device having asymmetric properties, a source of direct electrical energy, a line wire permanently connected at one end to a first terminal on said source, means connecting the other end of the line wire to one terminal of said device including an asymmetric unit poled to pass current only in the direction corresponding to the asymmetric properties of said device, a first electrical circuit for at times energizing the device including the line wire, the asymmetric unit, and a connection between the opposite terminal of the device and a second terminal of said source having the proper polarity with respect to said first terminal to cause current to flow through said asymmetric unit, a second electrical circuit for at other times energizing the device including a connection between said opposite terminal of the device and said first terminal of the source and a connection between said one terminal of the device and a third terminal of the source having a polarity with respect to the first terminal opposite to that of the second terminal of the source, said asymmetric unit being effective at such other times to block the flow of current through said line wire from said first source terminal.

10. Railway braking apparatus comprising a braking bar located in the trackway beside a track rail, a fluid pressure motor for operating the bar toward the rail into a braking position in which it will engage a part of a car to retard the speed of the car, a valve for controlling the admission of fluid to the motor, an electrical winding for operating the valve, first and second

pressure responsive devices subject to the pressure in the motor, first and second contacts respectively opened by said first and second pressure responsive devices at different pressures, and control apparatus for said winding according to claim 9, in which said first and second contacts are connected in said first and second circuits, and said electrical device is connected in parallel with the winding to delay deenergization thereof when said winding has previously been energized by direct current of a particular polarity to insure that the motor pressure continues to increase for a time after the contacts open.

11. Railway braking apparatus as in claim 10, in which said electrical device is an electrolytic condenser.

12. Railway braking apparatus comprising a braking bar located in the trackway beside a track rail, a fluid pressure motor for operating

track rail, a fluid pressure motor for operating the bar toward the rail into a braking position in which it will engage a part of a car to retard the speed of the car, a first electromagnetic valve effective when energized to cause admission of fluid to the motor, a second electromagnetic valve

effective when energized to cause exhausting of fluid from the motor, first and second pressure responsive devices subject to the pressure in the motor, first and second contacts respectively opened by said first and second pressure responsive devices.

sive devices at different pressures, means associated with said first valve to delay deenergization thereof when said winding has previously been energized by direct current of a particular polarity to insure that the motor pressure continues to increase for a time after the contacts

tinues to increase for a time after the contacts open, a source of direct electrical energy, a first line wire permanently connected at one end to a first terminal on said source, means connecting the other end of the line wire to one terminal of said first valve including an asymmetric unit

or said first valve including an asymmetric unit poled to pass current only in the direction corresponding to said particular polarity; a first electrical circuit for at times energizing the first valve including the line wire, the asymmetric unit, the first valve, and a first connection be-

tween the other terminal of said first valve and a second terminal on said source having the proper polarity with respect to said first terminal to cause current to flow through said asymmetric unit, said first connection including said first

contact and a second line wire; a second electrical circuit for at other times energizing the first valve including a second connection between said other terminal of the first valve and said first terminal of the source and a third connection between said one terminal of the first valve

tion between said one terminal of the first valve and a third terminal of the source having a polarity with respect to the first terminal opposite to that of the second terminal, one of said second and third connections including said second contact, said asymmetric unit being effec-

tive at such other times to block the flow of current through said first line wire from said first terminal; a third electrical circuit for at still other times energizing the second valve including said first line wire, said second valve, and for all times between the second

and a fourth connection between the second valve and said third terminal including said second line wire and a second asymmetric unit poled to pass current only from said first terminal to said third terminal, said first asymmetric unit being effective when said third circuit is completed and said first contact is closed to block the flow of current through said first circuit.

13. Control apparatus comprising a controlled electric device having asymmetric properties, a first circuit controller located adjacent said controlled device and having a contact, a second circuit controller located remotely from said controlled device and having two selectively closable contacts, a first line wire connected at one end to both contacts of said second controller, two oppositely poled asymmetric units connected to the other end of the line wire, a first connection between one asymmetric unit and one terminal of the controlled device including the contact of said first controller, a second connection between the other asymmetric unit and the other terminal of the controlled device, second and third line wires paralleling said first line wire and connected to said one terminal and said other terminal, respectively, of the controlled device, a first electric circuit for energizing said controlled device including one contact of said second controller, said first connection being effective when said one contact is closed to place said first controller in control of the controlled device, and a second electric circuit for energizing the controlled device including the other contact of said second controller, said first and second line wires and said second connection, said second circuit being effective when said other contact is closed to control said controlled device independently of said first controller, both of said circuits being effective when completed to supply electric potentials of the same polarity to the controlled device, said first line wire being effective to carry current in opposite directions in the two circuits.
